UNITED STATES PATENT OFFICE.

JOHN MULDER, OF ZEELAND, MICHIGAN.

AIR-HEATING FURNACE.

Application filed November 3, 1927. Serial No. 230,702.

The present invention relates to air-heating furnaces; and its object is, generally, to provide improved means for heating the air by the hot smoke and products of combustion issuing from the furnace, said means comprising passages for the air to be heated and passages for the smoke and such products arranged and combined compactly and controlled in an improved and effective manner; and further, to provide in such a structure such passages so arranged as to be readily cleaned.

This and any other and more specific objects hereinafter appearing are attained by, and the invention finds preferable embodiment in, the furnace structure hereinafter particularly described in the body of this specification and illustrated by the accompanying drawings, in which:

Figure 1 is a side elevational view of an air-heating furnace and its casings, certain parts being broken away;

Figure 2 is a vertical sectional view of a portion of the same taken on line 2—2 of Figure 3;

Figure 3 is a top plan view of the same; and

Figure 4 is a vertical sectional view of a portion of said structure taken on line 4—4 of Figure 3.

In the embodiment of the invention illustrated by these drawings, an air-heating furnace construction is shown including a furnace 1 of common form having the usual fuel door 2, ash door 3 and smoke pipe 4. A casing 5 surrounds this furnace at its sides and top in the ordinary manner being spaced therefrom to provide an air-heating chamber 6 from which the hot air pipes 7 lead to the rooms or parts of the building to be warmed. A second and outer casing 8 extending horizontally about the casing 5 and having a top wall 9, bottom wall 10, outer side wall 11 and front end walls 12, 13, is divided by horizontally spaced vertical partitions 14, 15 to form between them a passage 30 for smoke and products of combustion entering thereinto from the furnace at 16. These vertical partitions also separate on the opposite sides of said smoke passage a pair of air passages 17, 18 extending outside of and horizontally about the opposite sides respectively of the inner casing 5 and having said front end walls 12, 13, and cold air intakes 21, 22. Horizontally disposed partitions 23, 24 extend in these air passages

from the vertical partitions 15, 14 forwardly to front edges 19 spaced from the forward end walls 12, 13 as particularly well seen in Figure 1.

In these air passages 17, 18, smoke conduits 25, 26 lead from ports 27, 28 through the vertical partitions 15, 14 and are spaced from the other walls of said air passages. These conduits extend horizontally at 29, 31 above the horizontal partitions 23, 24, then downwardly at 34, 35 and spacedly from the edges 19 thereof and then below these horizontal partitions and horizontally reversely at 38, 39 to vents 36, 37 into the smoke passage 30 whence the smoke and products of combustion pass into and through the smoke pipe 4.

That the smoke, etc. may be made to pass into and through the conduits 25, 26 to warm the air in the passages 17, 18, or directly into the smoke pipe 4 as may be desired, the smoke passage 30 is divided by a vertical partition 40 having a smoke vent 41 therethrough and by a horizontal partition 42 thus forming a smoke passage 43 having the bottom wall 42 and said ports 27, 28. A valve is carried by the rock shaft 44 having a crank arm 46 to which is connected the operating rod 47. This valve has a member 48 closing the smoke vent 41 when the valve is turned to the position shown in solid lines in Figure 2, and has also a pair of opposite members 49, 50 opening the ports 27, 28 in said position of the valve. When however this valve is turned to the position seen in solid lines in Figure 4, the smoke vent 41 is opened and the ports 27, 28 are closed. This valve may thus be turned either to the position seen in solid lines in Figure 4 whereby the smoke and products of combustion pass in the ordinary manner into the smoke pipe 4, or to the position shown in solid lines in Figure 2 whereby the smoke, etc. must pass through the conduits 25, 26 to warm the air in the passages 17, 18 whence it is vented through pipes 51, 52 into the chamber 6 formed by the inner casing 5.

The partition 42 forming the bottom wall of smoke passage 43 is hingedly mounted at 53 and may be held in normal or horizontal position seen in Figure 2 by a supporting rod 54 pivoted thereto at 55, its free end resting on the closure 56 hingedly mounted at 57 and adapted to be held as by a latch 58 in horizontal position to close the openings 59 through the bottom wall 10 of casing 8.

This closure being opened and the rod 54 swung to permit the bottom wall 42 to fall to open position, any soot and the like deposited thereon will drop through the openings 59.

The conduits 25, 26 have openings indicated at 60 through which soot, etc. therein may be removed, such openings being closed by closures 61. The usual damper is shown 10 at 62 for the air opening 63 into the smoke passage.

The invention being intended to be pointed out in the claims, is not to be limited to or by details of construction of the particular embodiment thereof illustrated by the drawings or hereinbefore described.

I claim:

1. An air heater of the character described having a furnace with a smoke pipe, an air heating chamber surrounding the furnace provided with a hot air discharge pipe, an air passage outside said chamber extending horizontally about the same and venting thereinto, a smoke passage leading from the 20 furnace and provided with a port to the smoke pipe and a second port, a smoke conduit in the air passage extending from the second port and reversely to a vent into said smoke passage, and a valve controlling at least one of the ports.
2. An air heater of the character described having a furnace with a smoke pipe, an air heating chamber surrounding the furnace provided with a hot air discharge pipe, an 30 air passage outside said chamber extending horizontally about the same and venting thereinto, a smoke passage leading from the furnace and provided with a port to the smoke pipe and a second port, a smoke conduit in the air passage extending from the second port and reversely to a vent into said smoke passage, and a valve movable to a position closing either of the ports and opening the other port.
3. An air heater of the character described having a furnace with a smoke pipe, an air heating chamber surrounding the furnace provided with a hot air discharge pipe, an 40 air passage outside said chamber extending horizontally about the same venting thereinto and provided with a horizontal partition, a smoke passage leading from the furnace and provided with a port to the smoke pipe and a second port, a smoke conduit in the air passage extending from the second port and at one side of the partition then spacedly from the partition to the opposite side thereof and then to a vent into said smoke passage, and a valve movable to a position closing either of the ports and opening the other port.
4. An air heater of the character described having a furnace with a smoke pipe, an air

passage extending horizontally about the furnace and provided with a discharge vent, 65 a smoke passage leading from the furnace and provided with a port to the smoke pipe and a second port, a smoke conduit in the air passage extending horizontally from the second port and reversely to a vent into said smoke passage, and a valve controlling at least one of the ports.

5. An air heater of the character described having a furnace with a smoke pipe, a pair of air passages extending horizontally about 75 the opposite sides respectively of the furnace and provided with discharge vents, a smoke passage between the air passages leading from the furnace and provided with a port to the smoke pipe and a pair of other ports, 80 a smoke conduit in each air passage extending horizontally from one of said pair of ports and reversely to a vent into said smoke passage, and a valve movable to a position closing the first-mentioned port and opening said pair of ports and vice versa.

6. An air heater of the character described having a furnace with a smoke pipe, a casing surrounding the furnace forming an air heating chamber provided with hot air discharge pipes, a casing extending horizontally about the first-mentioned casing and provided with spaced vertical partitions forming between them a smoke passage leading from the furnace provided with a port to the smoke pipe and a pair of other ports through the partitions respectively said partitions also forming on the opposite sides of the smoke passage a pair of air passages extending horizontally about the opposite sides of the first-mentioned casing and venting thereinto each air passage having a horizontal partition, a smoke conduit in each air passage extending from one of said pair of ports and at one side of the horizontal partition then spacedly from the same to the opposite side thereof to a vent into said smoke passage, and a valve movable to a position closing the first-mentioned port and opening said pair of ports and vice versa.

7. In an air heater of the character described having a furnace with a smoke pipe, a casing forming a smoke passage leading from the furnace and having a port to the smoke pipe and a bottom wall with an opening therethrough, a hingedly mounted closure for said opening, means for releasably supporting the closure to close said opening, and a valve movable to a position closing the port and to another position opening the port and closing said opening additionally to the closure.

In testimony whereof I have hereunto set my hand at Grand Rapids, Michigan, this 28th day of October, 1927.

JOHN MULDER.
